INTERLOCKING ELEVATOR DOOR LATCH
SWITCHGael S. Rogers, Los Angeles, Calif., assignor to
Kimball Elevator Co., Ltd., Los Angeles, Calif.,
a corporation of California

Application September 18, 1948, Serial No. 49,946

4 Claims. (Cl. 200—55)

1

This invention relates to a latch mechanism for elevator hoistway entrance doors; more particularly it relates to such mechanism which is interlocked with the elevator controls to correlate the opening and closing of the doors with operation of the elevator.

It is an object of this invention to provide improved mechanism of this character.

It is another object of this invention to provide such mechanism adapted for mounting in a restricted space between the face of the entrance door and the hoistway edge of the door sill.

It is another object of the invention to provide such mechanism optionally useable with swinging or sliding entrance doors, either right hand or left hand opening.

It is another object of the invention to provide such mechanism incorporating improved switch means in which accidental closing of the switch is guarded against; wherein connection of the leads to the switch is facilitated; and in which the leads are protected from abrasion by the moving parts of the mechanism.

It is another object of this invention to provide such mechanism wherein the latch keeper is so arranged as to transmit any load imposed thereon by the entrance door, directly to the mechanism frame.

It is still another object of this invention to provide such mechanism having improved operating means for the latch keeper which simplifies installation of the mechanism under varying operating conditions.

It is still another object of this invention to provide a novel form of switch mechanism which requires that a pair of relatively movable members are in predetermined relation with respect to each other as well as with respect to the switch mechanism for closing the switch.

This invention possesses many other advantages, and has other objects which may be made more easily apparent from a consideration of several embodiments of the invention. For this purpose there are shown several forms in the drawings accompanying and forming part of the present specification. These forms will now be described in detail, illustrating the general principles of the invention; but it is to be understood that this detailed description is not to be taken in a limiting sense, since the scope of the invention is best defined by the appended claims.

In the accompanying drawings:

Figure 1 is an elevation, partly in section, showing the mechanism of the invention in use;

Figure 2 is a cross section, taken substantially as indicated by lines 2—2 on Figure 1;

2

Figure 3 is an elevation as seen from the right in Figure 1, showing a fragment of an elevator car landed at the entrance;

Figures 4, 5, 6 and 7 are detail sections taken substantially as indicated by correspondingly numbered lines on Figure 1;

Figure 8 is an elevation similar to Figure 1, but on a reduced scale and largely schematic, showing a modified form of the mechanism;

Figure 9 is a cross section on an enlarged scale, taken substantially as indicated by lines 9—9 of Figure 8;

Figure 10 is an elevation largely schematic, showing the mechanism installed with a different type of door;

Figure 11 is a cross section taken substantially as indicated by line 11—11 of Figure 10;

Figure 12 is an elevation largely schematic, showing the mechanism installed with another type of door; and

Figure 13 is a cross section taken substantially as indicated by line 13—13 of Figure 12.

Referring to the drawings; a latch mechanism incorporating the features of the invention and generally indicated by the letter M, is provided for each of the elevator hoistway entrance doors, and is mounted in the door opening or entrance E so as to overhang the upper inside corner of the door D when closed. This mechanism may supplement the usual hand operated latch. The mechanism M comprises a casing C providing spaced parallel faces 3 and 4 between which a keeper bar B is movably confined. The face adjacent the door D has an opening 5 across which the bar B is urged to extend in latching position, and through which latch member L mounted on the door D moves into and out of latching relation with respect to the bar B as the door is closed and opened. Thus, when the door D is closed, the latch member L is engaged by the keeper bar B and opening of the door D is prevented. An operator O, actuated in response to arrival of the elevator car at the floor level, is provided for operating the bar B to release the latch member L and allow the door to be opened. Switch means S cooperatively controlled by the bar B and the latch member L, are provided to prevent operation of the elevator unless the door D is closed and latched.

Referring in detail to the mechanism, the casing C comprises a rectangular open frame 6 with a back plate 7 and a cover plate 8 detachably secured to its opposite sides as by screws 9, and providing the parallel spaced faces 3 and 4. The casing C is mounted in the hoistway entrance E as by attachment to the hoistway wall W ad-

adjacent the entrance by screws 10. The plates 7 and 8 have respectively aligned apertures 11 and 12 adjacent their upper ends for mounting a shouldered pin 14 pivotally supporting the keeper bar B (see Figure 4).

The keeper bar B comprises a rectangular elongated portion 15 having a flat side 15-a which is adapted to slidably contact the face 3 and a pair of bosses 16 and 17 providing flat surfaces 16-a and 17-a slidably contacting the face 4, and joined by an intermediate portion 18. A light compression spring 20 confined between the portion 15 and the frame 6, resiliently urges the bar B in a clockwise direction. The bar B adjacent its upper end has oppositely directed transverse extensions 21 and 22 providing cam engaging surfaces 21-a and 22-a one of which, as 21-a, is adapted for engagement by a rotatable cam or operator 23 to cause the bar to swing about its pivot pin 14 in a counterclockwise direction against the force of the spring 20.

The cam 23 is fixed on one end of a shaft 24 which is rotatably supported in a bushing 25 threaded through one side of the frame 6. An arm 27 adjustably secured on the other end of the shaft 24, carries a roller 28 at its outer end which is adapted to be operated by means carried by the elevator car, as will be explained hereinafter. The arm 27 is provided with a counterbalance 30, so that there is no tendency for the shaft 24 to be turned due to any unbalance in the arm 27. A saw cut or split 27-a extends from shaft 24 through the counterbalance 30, to enable the arm 27 to be clamped in adjusted position on the shaft 24 by means of a screw 29 extending through the arm 27 adjacent the counterweight 30. A taper pin 29-a serves to fix the arm on the shaft permanently.

As clearly shown in Figure 4, the rotatable cam 23 is formed with two lobes 23-a and 23-b, either of which is adapted to engage the surface 21-a and swing the bar B counterclockwise out of latching position in accordance with the direction of rotation of the shaft 24. An important advantage of this arrangement is that the arm 27 may be mounted on the shaft 24 optionally to extend downwardly therefrom as shown by full lines in Figure 3, or to extend upwardly as shown at 27-b by the dotted lines. This facilitates installation of the mechanism, since it is thus more adaptable to different conditions, such as various door heights, under which it must be used. Furthermore, as will appear presently, it facilitates use of the mechanism with right or left hand opening doors.

Detent means comprising a spring finger 35 are provided for releasably maintaining the bar B out of latching position. The free end of finger 35 is bent inwardly substantially at a right angle to provide a tooth 35-a adapted to engage the forward edge of the bar 15 and then bent outwardly from the tooth to provide an extension 35-b adapted to be engaged by the latch member L. The other end of the finger 35 is bent inwardly and then outwardly to provide a mounting ear 35-c which is slotted at 35-d to accommodate the mounting screw 36 extending through the side of the frame 6. The frame 6 is thickened to provide a shoulder 6-a, engaging the upper edge of the ear 35-c to maintain the finger against rotation about the screw 36. Thus, a single screw 36 suffices to mount the finger 35, the slot 35-d permitting horizontal adjustment of the finger when the screw 36 is loosened.

The opening 5 for the latch member L extends

through the back plate 7, against which the door D closes. The latch member L is of hook-like form, having an enlarged base 37 for accommodating screws 38 which attach the member L to the door D, and which is joined by a reduced shank 39 to the head 40. The head 40 overhangs the base 37 cooperating therewith to provide a slot 41 for accommodating the intermediate portion 18 of the keeper bar B.

The arrangement is such that when the door D is closed the latch member L extends into the casing C a distance such that slot 41 is aligned with portion 18 of the bar B. Thus, if the detent finger 35 is caused to release the keeper bar B the bar will swing downwardly into the slot 41 securing the door against opening. For releasing the detent finger 35, the head 40 is arranged to engage the finger extension 35-b, as the door D approaches closed position, and force the finger 35 outwardly so that the tooth 35-a clears the bar portion 18.

To provide for proper operation in case the bar B should for any reason reach its latching position across the opening 5 before the latch member L is in its proper relative position, the back of the intermediate portion of the bar B is bevelled as at 18-a, and the head 40 is correspondingly bevelled as at 40-a. Thus, if the door D is closed with the keeper bar B in latching position, the engagement of the bevelled surfaces 18-a and 40-a will cause the bar B to swing counterclockwise and clear the head 40 as the head enters the casing C. The finger extension 35-b may be correspondingly inclined to cooperate with the surface 40-a and cause the finger 35 to release the bar appropriately.

To properly position the bar B when released, an adjustable stop is provided. This is shown as comprising a set screw 42 threaded through the top of the frame 6 and adapted to engage the transverse extension 22 on the keeper bar B.

The switch means S which interlocks the door latch mechanism M and the elevator controls comprises a pair of contacts 43 and 44 supported on opposite sides vertically of the casing opening 5, by an insulating block 45. This block 45 is demountably secured in the casing C to facilitate attachment of the leads to the contacts 43 and 44 and provides a channel for the lead 43-a to the upper contact 43 so that the lead is prevented from contacting the moving parts of the mechanism, thus being protected from abrasion thereby.

For this purpose the frame 6 has a pair of opposed grooves 6-b and 6-c formed therein for slidably accommodating respectively the opposite ends of the block 45. The block is of less width than the frame 6 and has a plurality of lugs 45-a spaced from the back of the block 45 and projecting therefrom the full width of the frame 6. Thus, with the block 45 positioned in the grooves 6-b and 6-c, the cover plate 8 by engaging the lugs 45-a will maintain the block 45 against the back plate 7 and spaced from the plate 8, the lugs 45-a serving to confine the lead 43-a in the space thus provided.

The contacts 43 and 44 are substantially identical, thus a description of one, for example contact 44, will suffice for both, reference for this purpose being had to Figure 6. The contact member 44 comprises a head 44-a and a shank 44-b threadedly engaging a through opening 45-b in the block 45 and extending therein a suitable distance to locate the head 44-a properly with respect to the other elements of the

switch mechanism S. The opening 45-b has a counterbore or enlarged portion 45-c forming a shoulder 45-d. The inner end of shank 44-b is tubular, so that after proper positioning of the head 44-a the shank 44-b is bellied out or riveted over against the shoulder 45-d. This operation also distorts the threads on the inner end of the shank 44-b. The opening 45-c is then filled with a suitable insulating compound which after hardening prevents access to the inner end of the shank and together with the riveted over portion and the distorted threads, securely holds the contact member 44 against movement in the block 45.

The latch member L when the door is closed, is positioned intermediate the contacts 43 and 44 and carries a conductor 47. This conductor 47 (Figures 1 and 7) comprises identical upper and lower contact blocks 48 and 49 secured respectively in grooves 50-a and 51-a formed in the insulating blocks 50 and 51. These blocks 50 and 51 have tongues or portions of reduced width 50-b and 51-b accommodated respectively in grooves 40-b and 40-c formed in the upper and lower sides of the latch member head 40. A single bar or rivet 52 of conducting material extends through the head 40, the insulating blocks 50 and 51 and the contact blocks 48 and 49 and secures the blocks in assembled relation on the head 40 by riveting over its opposite ends to form countersunk heads 52-a. An insulating sleeve or tube 53 prevents contact between the rivet 52 and the head 40 and extends a short distance into counterbores 50-c and 51-c provided respectively in the insulating blocks 50 and 51 to prevent entry of liquid and possible grounding of the contacts.

The keeper bar B carries a pair of contactors 54 and 55 adapted to engage the opposite ends respectively of the conductor 47 and the contacts 43 and 44. Since these contactors and their mountings are substantially identical, only one will be described. Thus, boss 16 has a through opening 16-b in which an insulating bushing 56 is secured as by a press fit. This bushing 56 has a flat metal key 57 with a T head 57-a, secured therein, slidably mounting a conducting element 58 which confines a light compression spring 59 against the bushing 56. The conducting element 58 has a slotted opening 58-a accommodating the key 57, thus maintaining the element 58 against rotation, the head 57-a preventing the member 58 being forced off the key 57 by the spring 59. The other contactor 55 is similarly mounted on boss 17.

The arrangement is such that contacts 43 and 44 are bridged or connected only when the latch member L and the keeper bar B are in latching engagement, such connection being from contact 43, via contactor 54, conductor 47 and contactor 55 to contact 44. Obviously, movement of the keeper bar B to latching position will be ineffective to connect the contacts, unless the door D is closed, and the latch member L is engaged by the keeper bar B. Similarly, closing of the door D will be ineffective to connect the contacts, until latched by the member B.

The mounting and operation of the mechanism M in connection with an elevator hoistway entrance door will now be described. The mechanism just discussed is arranged for use with a conventional right hand swinging door, and as shown in Figures 1 and 3 is secured to the hoistway wall adjacent the door jamb 60 just beneath the lintel 61.

As is well understood conventional automatic elevators are provided with means for operating the latch mechanism for the hoistway entrance doors to unlatch the doors for opening when the elevator car is levelled at the respective floor and to prevent movement of the car until the door is closed and latched. Such means usually comprises a retiring cam 62 carried by the elevator car and which is normally maintained in position to clear the operating arm cam follower 28, but which moves to a position in which it will engage this follower 28 causing the operator O to swing the keeper bar B from latching position as the elevator car reaches the floor. This opens the switch S so that the elevator cage cannot be moved and releases the door D so that it can be opened. When it is desired to operate the elevator car, the retiring cam 62 is caused to return to its normal position releasing the cam follower 28 and allowing the keeper bar B to return to its latching position. If the door D has already been closed, it will be latched by the bar B and contacts 43 and 44 connected together. If the door D has not been closed, the contacts 43 and 44 will not be connected and the elevator car cannot be moved. However, the door D can just as well be closed after the return of bar B to its latching position, which will cause the door to be latched as previously discussed, and contacts 43 and 44 to be connected, permitting operation of the elevator as before.

An important feature of the mechanism M is that it is readily adaptable to other types of doors than that just described, since the back plate 7 and the cover plate 8 are interchangeable and the frame and other parts such as the cam 23 for releasing the keeper bar are symmetrical about a vertical medial plane of the assembled mechanism. Thus, considering the door just described as a right hand swinging door, the parts can readily be assembled in reversed relationship as shown in Figures 8 and 9, enabling use of the mechanism with a door swinging in the opposite direction or a left hand swinging door. The keeper bar B however must be provided with a bevelled surface 18-b, oppositely directed from the surface 18-a, for engagement by the surface 40-a on the latch member L when used with a left hand opening door; also, the contactors 54 and 55 must be disposed on the opposite side of the bar B.

Furthermore, the mechanism may be used with sliding doors by mounting the casing at right angles with the direction of movement of the door, as shown in Figures 10 to 13. Figures 10 and 11 show what may be termed conveniently a left hand sliding door, and brief consideration will show that mechanism as described for a right hand swinging door is equally suitable in this environment and conversely, mechanism for a left hand swinging door is suitable for an oppositely opening or right hand sliding door, Figures 12 and 13. In this way, a small stock of parts will enable a dealer or service man to cover all the usual types of installations. In all cases it is to be understood that the retiring cam 62 is appropriately located on the elevator car for cooperation with the operating arm 27.

I claim:

1. In an interlocking door latch: a movable keeper bar; a latch member adapted for mounting on the door, for movement therewith, transversely of said bar; said bar being movable into latching engagement with said member when said door is closed, said member being adapted to

engage said bar intermediate its ends; a pair of contacts; stationary means supporting said contacts so as to be positioned on opposite sides of said member when said door is closed; a conductor carried by said member intermediate said contacts; and a pair of resilient contact elements carried by said bar for respectively contacting the opposite ends of said conductor and the adjacent contact, whereby to electrically connect said contacts when said member and said bar are in latching engagement.

2. In an interlocking door latch: a latch member adapted for mounting on the door; a keeper member movable into and out of latching position and adapted to engage said latch member when the door is closed and said latch member is in latching position; a pair of contacts spaced from one of said members in the direction in which said member is movable; a conductor carried by one of said members, adapted to be positioned adjacent said contacts when said one member is in latching position; and a pair of contactors carried by the other member for respectively engaging said conductor and said contacts for electrically connecting said contacts.

3. In a door latch mechanism: a latch member adapted for mounting on the door; a keeper member movable into and out of latching position and adapted to engage said latch member when the door is closed and said latch member is in latching position; a pair of stationary spaced contacts adapted to be connected respectively with opposite sides of an electric circuit; a conductor carried by said latch member, so positioned as to be intermediate said contacts when said latch member is in latching position, said conductor comprising a pair of conducting elements on opposite sides of said latch member, and a conducting bar extending through said latch member, electrically joining said elements and securing them in assembled relation on said latch member; and a pair of contactors carried by said keeper member for respectively engaging said elements and said contacts when said keeper member and said latch member are in latching relation for electrically connecting said contacts.

4. In a door latch mechanism: a latch member adapted for mounting on the door; a keeper

member movable into and out of latching position and adapted to engage said latch member when the door is closed and said latch member is in latching position; a pair of stationary spaced contacts adapted to be connected respectively with opposite sides of an electric circuit; a conductor carried by said latch member, so positioned as to be intermediate said contacts when said latch member is in latching position, said latch member being of electrically conducting material; said conductor comprising a pair of insulators respectively on opposite sides of said latch member, a pair of conducting elements respectively on said insulators, a conducting bar extending through said latch member electrically joining said elements and securing said elements and said insulators in assembled relation on said latch member, an insulating sleeve about said bar, extending through said latch member and into recesses respectively in said insulators; and a pair of contactors carried by said keeper member for respectively engaging said elements and said contacts when said keeper member and said latch member are in latching relation for electrically connecting said contacts.
